PENCIL

Filed March 27, 1919

Inventor:
Howard Pische,

UNITED STATES PATENT OFFICE

HOWARD L. FISCHER, OF ST. PAUL, MINNESOTA, ASSIGNOR TO BROWN & BIGELOW,
OF ST. PAUL, MINNESOTA, A CORPORATION OF MINNESOTA

PENCIL

Application filed March 27, 1919. Serial No. 285,708.

This invention relates to a pencil of a very simple construction which is adapted to hold a marking lead of a very small diameter in readiness for use, so as to be projected or withdrawn into the pencil barrel at will. The marking lead held in writing position can be of a considerable length, owing to the simplicity of the construction of the lead propelling means, thus giving a pencil construction which is desirable because it does not need to be filled as often as where a shorter lead is used.

The construction of this pencil also provides a peculiar lead holding means for the lead in writing position and a lead magazine for extra leads, whereby a considerable amount of writing lead can be carried in a convenient manner in the pencil barrel. The lead holding means is adapted to slidably hold the butt or rear end of the marking lead in writing position in the pencil. It is very desirable, in a pencil of this nature, to have a simple construction and this invention carries out this idea in a practical way.

In the drawing forming part of this specification:

Figure 1 is a longitudinal cross section of the pencil.

Figure 2 is a longitudinal cross section of the pencil barrel with the propelling mechanism removed therefrom.

Figure 3 is a section on the line 3—3 of Figure 2.

Figure 4 is a perspective view of the propelling mechanism and lead holding means with the marking lead therein, as it would appear when removed from the pencil barrel.

Figure 5 is a perspective view of a portion of the pencil.

Figure 6 is a detail of a portion of the pencil, partially illustrated in cross section.

The pencil A is provided with a barrel 1, which is formed of thin, hollow tubing with a conical hollow forward end 2, the apex 3 of which is provided with an axial opening 4, which is approximately the same diameter or shape as the cross section of a fine marking lead 5, which is adapted to be used therein. The marking lead 5 is of a con-

siderable length and its body portion extends unsupported between its ends through the hollow forward chamber 6 of the pencil A. The rear end of the marking lead is frictionally engaged by the socket or sleeve 7 and the forward end of the lead is held in the opening 4. The socket 7 is slidably and pivotally held to a supporting rod or arm 8 by means of a coil spring 9; the forward free end 10 of the rod 8 projecting a very short distance into the socket 7 and the socket being freely slidable on the end of the rod. One end of the coil spring 9 is secured to the rear portion of the socket 7 by having the coils of the springs engage in the recesses or grooves 11 formed in the socket, and the other end of the spring 9 has its coils engaging in grooves or threads 12 formed in the rod 8. It is evident, however, that the ends of the coil spring 9 can be soldered or otherwise attached to the collar 7 and the rod 8. This construction of holding means for the rear end of the marking lead is adapted to hold a lead so that when the same is ejected from the pencil and is worn off to such an extent that the forward edge 13 of the collar or socket 7 engages the inner surface 14 of the hollow conical end 2 of the pencil barrel 1, the end 10 of the rod 8 will slide forward in the socket 7 and expel all of the marking lead out of the pencil as the propelling means of the pencil is operated. On the other hand, the rod 8 only projects far enough into the rear end of the socket 7 to pivotally hold the rear end of the marking lead 5, thus allowing for any irregularities in the barrel construction and giving sufficient movement to the rear portion of the marking lead held in writing position to prevent breaking of the same, in most instances, if the pencil is dropped when in use.

A propelling means B, which is removable from the pencil barrel 1, is provided to project the marking lead from the writing end of the pencil, as required, or to withdraw it into the pencil when the propelling mechanism is operated. The propelling mechanism B consists of a threaded member or rod 15 which extends into the rear end of the pencil barrel 1, and is rigidly secured 100

by means of its thread and the nut 16 to an operating head 17, together with the threaded rod 15, are swivelly or rotatably held by the collar closure 18, which is formed with a forward threaded end 19 which is adapted to engage in the threaded collar 20 which is rigidly held by friction, or otherwise, in the enlarged rear portion 21 of the barrel 1. When the collar closure 18 is screwed tight into the threaded sleeve 20 in the pencil A, the threaded rod 15 is held against longitudinal movement therein, but is freely rotatable by engaging and rotating the head 17 and can be rotated in either direction to operate the threaded rod or member 15.

A threaded nut or member 22 is adapted to be carried by the rod or threaded element 15 and the element or nut 22 is shaped as to frictionally engage in the channel of passageway 23 formed by the channel shaped member 24, when the propelling mechanism is in position in the pencil barrel. The channel shaped member 24 is formed of thin material, and is frictionally or other rigidly held in the hollow portion of the barrel 1 of the pencil A, being of a suitable shape and provided with a longitudinally extending rib 25, the edge of which engages against the inner surface of the barrel and causes the longitudinal edges 26 and 27 to also engage the inner surface of the barrel 1, to hold the channel member 24 in position in the barrel. It is obvious that the channel member can be inserted in any position in the barrel, but it must frictionally engage the inner surface of the barrel to hold it rigidly in position, or be otherwise rigidly secured therein, where the cross section of the barrel 1 is circular in shape. A slanting flange 28 is rigidly secured to one end of the channel member 24 to form a closure for the forward end of the chambers 29 and 30 formed about the outer surface of the channel member 24 and by the barrel casing 1. The chambers 29 and 30 are for the purpose of forming a magazine for holding extra leads 5, as indicated in Figures 1, 2 and 3, in this manner conveniently and simply forming a magazine for the marking leads, which are of a very long length in proportion to the dimensions of the pencil A. The passageway or chambers 23, formed by the channel member 24 and the barrel casing 1, are for the purpose of receiving the threaded element or rod 15 and the nut 22. The nut 22 frictionally engages the inner surface of the passageway or chamber 23, slightly, so as to hold it against free movement therein, and to hold it against rotation but to allow it to move longitudinally therein when in position in the pencil barrel, as illustrated in Figure 1, and when the operating head 17 is rotated. The rear end of the rod 8 is rigidly secured 65 at 31 to the nut 22 so that when the nut 22 is

moved longitudinally, by rotating the head 17 and the threaded driving member 15, the marking lead 5, held in writing position in the pencil, will be moved longitudinally in either direction, according to the rotation 70 of the member 15.

The head 17, which is swivelly or rotatably held by the collar 18, has its forward edge expanded so as to form an annular shoulder 32, which engages the forward end of the threaded end portion of the collar 18 to hold the collar 18 against the shoulder 33 of the head 17, thus holding the collar 18 freely rotatable on, but against removal from the forward end of the head 17. The forward, 75 hollow end of the head 17, which projects through the collar 18, forms a recess 34 which will readily receive the ends of the marking leads 5 held in the magazine chambers 29 and 30, if the collar closure 18 is unscrewed 80 and the writing end of the pencil is held upward, causing the rear ends of the marking leads in the magazine chambers 29 and 30 to slide into the recess 34 and thus preventing them from falling out of the pencil on to the floor when the pencil is opened and the ejecting means B is being removed therefrom. The collar closure 18 forms a closure for the magazine chambers 29 and 30. A recess 35 is formed in the rear end of the head 17, 85 which is adapted to receive an eraser 36, as illustrated in Figure 1. When the eraser 36 wears down the portion of the same in the recess 35 can be ejected either by degrees or entirely from the recess 35 by loosening the nut 16 and operating the threaded rod 15 to force the eraser out of the recess.

When the marking lead held in writing position is entirely used up, and it is desired to put a new marking lead into the socket 7, the head 17 is rotated in a backward direction, causing the nut 22 to travel backwardly on the threaded member or rod 15 to its rear-most position, whereupon the collar closure 18 will be caused to unscrew, or can be engaged and unscrewed, and the propelling mechanism withdrawn from the pencil barrel. A new marking lead 5 is then inserted in the socket 7 and the propelling mechanism B again inserted in the chamber or channel 23, while the collar 18 is screwed fast to the pencil barrel, whereupon the pencil is again ready for use.

The pencil barrel 1 can be formed of a hexagon cross section as illustrated in Figures 7 and 8 and a threaded nut member 22 of a similar cross section so as to properly engage the inner surface of the hexagon barrel. In this construction, the marking leads 5 are held in suitable sockets 37, formed in the threaded nut 22 which is adapted to travel back and forth in the barrel when the projecting mechanism is operated by the operating head 17. With this hexagon construction or shape of barrel, it is not neces-

sary to use the channel member such as 24, to hold the threaded nut against rotation while the space about the projecting mechanism forms a suitable magazine for holding extra marking leads. The operating head 17 of the projecting mechanism forms a closure for the rear end of the pencil barrel and magazine.

The construction of this pencil is extremely simple, but it is obvious that it will effectively hold a marking lead in a practical way, so that it can be projected or withdrawn into the pencil barrel, as may be desired. There are very few parts required in the construction of this pencil, thus giving an inexpensive device.

The operating head 17 and closure 18 are removable as a unit from the barrel 1 and the magazine portion can also be easily removed, if it is desired, where it is frictionally held in the pencil casing, this construction allowing the pencil casing 1 to be made up and printed upon, if desired, before the magazine channel member 24 is inserted therein. This is important for various uses of the pencil. There are no complicated parts and the removal of the operating parts, collectively, gives a pencil construction where, if it is desired, owing to the defectiveness, or otherwise, the propelling mechanism can be easily replaced by a new portion or part, and thus give the user of the pencil, a practical device, which is not likely to get out of order, and being very cheap to manufacture, still giving a pencil of a neat and desirable appearance.

The slanted flange or closure 28, at the forward end of the channel member 24, prevents any of the particles of lead, which may be broken off from the marking lead in writing position, from being held in the pencil barrel when the propelling mechanism is removed therefrom, but on the other hand, tends to cause them to be discharged when the pencil is held conical end upward with the propelling mechanism removed therefrom.

The operating head 17 and the closure 18, which are of any suitable shape, are connected together as a unit and form an extension of the rear end of the pencil barrel, while the closure collar 18 is positioned adjacent the operating head 17 and is freely rotatable to lock the unit to the barrel or disengage it when desired. The threaded rod 15 is attached to the unit and is removable from the casing, with the operating unit.

In accordance with the patent statutes I have described the principles of operation, of my invention, together with the apparatus which I now consider to represent the best embodiment thereof, but I desire to have it understood that the construction shown is only illustrative and that the invention can be carried out by other means and applied to

uses other than those above set forth within the scope of the following claims:

I claim:

1. A pencil having means within its body for propelling a lead, an actuating means including members arranged end to end, cooperating portions on said members whereby one of said members forms a locking means to hold the actuating means within said body, the other of said members being operable to operate said actuating means.

2. A pencil having a body within which is mechanism for propelling a lead, rotatable actuating means therefor mounted exteriorly of the body at its upper end, and a connection between the body and actuating means consisting of a threaded member secured to the upper end of the pencil, and a member having freely rotatable connection with the actuating means and threaded to engage with the first mentioned threaded member, substantially as described.

3. A pencil having means within its body for propelling a lead, and actuating means therefor consisting of a collar and sleeve arranged end to end, the former stationary and the latter rotatable with respect to the body, and means providing freely rotatable and inseparable connection between the collar and sleeve invisible when the parts are assembled upon the pencil, the sleeve being operatively connected to the lead propelling means, and the collar being detachably secured to the pencil body, substantially as described.

4. A pencil comprising a barrel, a channel shaped member extending longitudinally into said barrel and being in part spaced from the barrel to form with the wall of the barrel a lead magazine, said channel shaped member having spaced side walls adapted to frictionally engage the wall of the barrel to hold the said member fixedly thereto, a lead propelling means adapted to operate in the channel of said member, and a head on said propelling means adapted to close said magazine and operate said propelling means.

5. A pencil comprising a barrel, a channel shaped member extending longitudinally into said barrel and being in part spaced from the barrel to form with the wall of the barrel a lead magazine, said channel shaped member having spaced side walls adapted to frictionally engage the wall of the barrel to hold said member fixed thereto, a lead propelling means adapted to operate in the channel of said member, said lead propelling means including a rod and a nut engaging the rod to travel thereon, the spaced side walls of the said member serving to hold the nut of the propelling means against rotation while permitting the same to slide longitudinally thereon, and a head on said propelling means adapted to close said magazine and operate said propelling means.

6. A pencil comprising a barrel, a channel

shaped member of general U-shape form in cross section extending longitudinally into said barrel, said channel shaped member having means for spacing the same from the wall of the barrel, and forming with the wall of the barrel a magazine, the spaced side walls of said member being adapted to frictionally engage the wall of the barrel to hold said member fixed thereto, a lead propelling means adapted to operate in the channel of said member, and a head on said propelling means adapted to close said magazine and operate said propelling means.

7. A pencil comprising a barrel, a channel shaped member of general U-shape form in cross section extending longitudinally into said barrel, said channel shaped member having means for spacing the same from the wall of the barrel, and forming with the wall of the barrel a magazine, the spaced side walls of said member being adapted to frictionally engage the wall of the barrel to hold said member fixed thereto, said channel member having a flange at its lower end slanting downwardly and outwardly therefrom, a lead propelling means adapted to operate in the channel of said member, and a head on said propelling means adapted to close said magazine and operate said propelling means.

8. A pencil comprising a barrel, a channel shaped member extending longitudinally into the barrel and forming with the wall of the barrel a magazine, said channel shaped member being of general U-shaped form in cross section and having a longitudinally extending rib projecting from its outer face intermediate its longitudinal edge portions, said rib and longitudinal free edge portions of said member being adapted to frictionally engage the wall of the barrel to hold said member fixed thereto, a lead propelling means adapted to operate in the channel of the said member, and a head on said propelling means adapted to close said magazine and operate said propelling means.

9. A pencil comprising a barrel, a channel shaped member extending longitudinally into the barrel and forming with the wall of the barrel a magazine, said channel shaped member being of general U-shaped form in cross section and having a longitudinally extending rib projecting from its outer face centrally of its longitudinal edge portions, said rib and the longitudinal free edge portions of said member being adapted to frictionally engage the wall of the barrel to hold said member fixed thereto, a lead propelling means adapted to operate in the channel of the said member, and a head on said propelling means adapted to close said magazine and operate said propelling means.

10. A pencil having within its body lead propelling means, actuating means for the lead propelling means, said propelling

means including an ejector rod and a lead socket supported by spring means to normally project beyond the forward end of the ejector rod and providing for relative movement between the ejector rod and lead socket under tension of the spring means on engagement of the socket with the writing end portion of the pencil to expel the butt of the marking lead in said socket.

11. A pencil including a casing, a channel member held against rotation within said casing, said channel member being of a construction to have a three-point engagement with the casing to provide spaces between the exterior of the channel member and the casing and form therewith a magazine for leads, and a lead propelling means having a part thereof engaging the channel member and held thereby against rotation.

12. A pencil including a casing, a lead propelling means comprising a threaded member, a nut adapted to engage said threaded member, a rod extending from said nut, and a channel means within said casing adapted to hold said nut against rotation, said channel means being in part spaced from the casing to form therewith a lead magazine.

13. A pencil including a casing, a channel means held against rotation in said casing, said channel means being in part spaced from the casing to form therewith a lead magazine, and a lead ejecting means operable in said channel means and having a part thereof engaging with and held from rotation by the channel means.

14. A pencil including a casing, a lead ejecting means, a channel means held against rotation within said casing, said channel means being in part spaced from the casing to form therewith a lead magazine, and an out-of-round opening extending through said channel means adapted to receive the lead ejecting means, said lead ejecting means having a part thereof engaging with and held from rotation by the channel means.

15. A pencil including a shell like casing, a shell like channel member within the casing, said channel member being held in said casing by frictional engagement therewith and being in part spaced from the casing to provide therewith a lead magazine, said channel member having a longitudinal passageway therethrough with an out-of-round cross sectional shape, and said lead ejecting means having a part thereof engaging and co-operating with the channel means.

16. A pencil including a lead propelling means and operating means therefor, and an eraser socket in said operating means, said propelling means including a part associated with said eraser socket and adapted to be operated to eject the eraser from said socket.

HOWARD L. FISCHER.
